UNITED STATES PATENT OFFICE

RONALD B. NOBLE, OF SPOKANE, WASHINGTON

BEARING PULLER

Application filed February 23, 1929. Serial No. 342,071.

My invention relates to bearing pullers and is an improvement over my prior patent of the same title, Number 1,640,904 and issued August 30, 1927. Certain objects of my present invention are to provide a bearing puller that is simpler in construction, easier to assemble, comparatively less expensive to manufacture and which is more efficient in its use than my former device. In the attainment 10 of the foregoing objects I have provided a simplified spring arrangement for retaining the side jaws in a normally open position, improved gripping ends for the jaws, detachable wings, and other simplified structural de- 15 tails.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a plan view of my device with 25 its side jaws held in a vise and with its notched gripping ends in engagement with the bearing of an electric motor and with its screwbar engaging the motor shaft in position for removing the motor bearing;

Fig. 2 is a fragmentary plan view showing the gripping ends of the side jaws with their flat inner recessed walls in engagement for removing a gear wheel from its shaft;

Fig. 3 is a reversed perspective view of the 30 device and showing, in dotted lines, an ordinary clamp holding the side jaws in constrained engagement with a motor bearing and also showing the detachable wings in dotted lines;

Fig. 4 is a fragmentary perspective view showing the inner side of one of the jaw gripping ends;

Fig. 5 is a view in end elevation of the jaws showing their notched gripping ends in four point engagement with a bearing;

Fig. 6 is a view in perspective of one of the detachable wings; and

Fig. 7 is a view in transverse section through one of the side jaws and wings.

50 Referring to the drawings throughout

which like reference numerals designate like parts, the numeral 5 indicates a cross-head having slots 6 in its ends and semiannular transverse grooves 7 in its outer corners. Side jaws 8 have reduced shanks 9 that fit snugly within said slots, and cylindrical lugs 10 on the outer ends of said shanks bear snugly within said transverse grooves to form detachable hinge joints.

A flat expansion spring 11 has its ends respectively secured to lugs formed on said jaws and normally retains the jaws in an open position. Stops 13 are formed on the inner side of the crosshead 5 that are arranged to engage shoulders 14 formed on the jaws at the inner ends of the shanks 9 and thus retain the spring from causing said jaws to swing wide open as will be understood.

The gripping ends of the side jaws 8 are rounded on their exterior portions while their interior portions are recessed at 15 to form flat end walls 16 for reasons presently set forth. Said ends are notched in angular fashion at 17 and beveled at 18 to provide effective means for engaging a bearing at 75 four points as designated by the numeral 19 in Fig. 5.

Detachable wings 20 are provided for the jaws 8 and are formed of spring metal with right angle flanges 21 having annular depressed bosses 22 that register with corresponding indentations 23 in the sides of said jaws to hold the wings in position. Said flanges are also provided with right angle bottom portions 24 that fit snugly against the undersides of said jaws and have upstanding spring lips 25 that serve as additional securing means by holding said flanges in compression against the sides of said jaws. It will be obvious that said wings may be readily attached to and detached from the jaws.

A screwbar 26 is threaded centrally through the crosshead 5 and is provided on its inner end with a conical engaging point 27 and on its outer end with an angular head 28 adapted to be turned with a wrench or the like.

In the practical use of my device the gripping ends of the jaws 8 are placed in engagement with a bearing 29 of a motor 30 or the

like, such as shown in Figs. 1 and 5, with its edges 18 in engagement therewith. Said jaws are clamped between a vise 31 with the wings 20 resting on its top as shown in Fig. 1 and thus holding said jaw edges securely in engagement with the bearing that is to be removed. The screwbar 26 is then set up until its point 27 centrally engages the shaft 32 of the motor. It will now be apparent that the bearing may be pulled from the motor by further turning the screwbar with a wrench.

In cases where a vise is not available an ordinary clamp, as shown in dotted lines in Fig. 3, may be used. In this case I usually provide depressions in the ends of the jaws, such as shown at 33, for engagement by the clamp and to prevent same from slipping as will be understood.

Referring to Fig. 2, in the removal of a gear 34 or the like its periphery is disposed within the recesses 15 with the flat walls 16 in engagement with the side of the gear which is then removed in the previously described manner.

Having thus described my invention what I claim and desire to secure by Letters Patent of the United States is:—

A bearing puller comprising a crosshead, a screwbar, side jaws detachably hinged to the crosshead, a flat spring arranged to retain the jaws in a normally open position, means for limiting the opening movement of the jaws, the gripping ends of the jaws having recesses and flat walls, detachable wings for the jaws, and means for resiliently retaining the wings in place.

In testimony whereof I affix my signature.
RONALD B. NOBLE.
